ANDREW H. CANDEE, OF PITTSBURGH, PENNSYLVANIA, ASSIGNOR TO WESTINGHOUSE ELECTRIC & MANUFACTURING COMPANY, A CORPORATION OF PENNSYLVANIA.

CENTRIFUGAL FAN.

1,378,008.

Specification of Letters Patent. Patented May 17, 1921.

Application filed October 21, 1916. Serial No. 126,892.

To all whom it may concern:

Be it known that I, ANDREW H. CANDEE, a citizen of the United States, and a resident of Pittsburgh, in the county of Allegheny 5 and State of Pennsylvania, have invented a new and useful Improvement in Centrifugal Fans, of which the following is a specification.

My invention relates to centrifugal fans 10 and particularly to fans or pumps in which the fluid to be moved is taken in longitudinally, with respect to the axis of rotation, and is discharged circumferentially.

In my copending application, Serial No. 15 96,058, filed May 8, 1916, is shown and described a centrifugal fan in which bracing members are disposed obliquely between the end plates of the fan in order to prevent relative angular movement of the plates during 20 the operation of the fan. In order to provide a perfectly rigid structure, it is desirable to place the bracing members in a state of tension but, as the respective axes of the bracing members are at an angle to 25 the fan plates, it has heretofore been found difficult to so secure the bracing members to the plates that they will not tear out when the bracing members are in tension.

The object of my invention is to provide 30 a novel means of securing the bracing members to one or both of the plates so that the tension of the bracing members will be transmitted to a plane that is substantially normal to the respective axes of the bracing members.

A further object of my invention is to provide means whereby the tension of the bracing members may be readily adjusted.

In the accompanying drawings, Figure 1 40 is a perspective view of a centrifugal fan embodying my invention; Fig. 2 is a view, similar to Fig. 1, showing a modification of my invention; Fig. 3 is an enlarged fragmentary view showing the relation of one 45 of the bracing members (shown in Fig. 1) to the fan plates, and Figs. 4 and 5 are detail views of one of the members shown in Fig. 3.

The fan comprises a hub 1 that is provided 50 with a flared-out flange 2 which is surrounded by an annular plate 3. The plate 3 may be either formed integral with the hub or may be secured thereto in any suitable manner. A second annular plate 4 is spaced 55 from the plate 3 by a plurality of blades

5 that are circumferentially arranged in spaced relation between the plates and extend at right angles thereto. The fan, as a whole, is adapted to be mounted on the shaft of a suitable motor (not shown) and the rotation of the blades 5, during the operation of the motor, draws air into the fan in a longitudinal direction, with respect to the axis of rotation, and discharges it tangentially. It has been found, however, that, during acceleration or deceleration of the fan, the ring 4 and the portions of the blades 5 adjacent thereto tend to lag behind or advance ahead of the ring 3 which is connected rigidly to the driving shaft, owing 60 to the inertia of these parts. Consequently, when the direction of rotation of the driving shaft changes, the forces due to the gyroscopic action and inertia tend to cause relative movement of the rings 3 and 4. In 65 order to remedy this undesirable effect, bracing members 6 are secured between the plates, with their respective longitudinal axes extending at an angle thereto.

The bracing members 6 are oppositely inclined with respect to each other, and the adjacent ends of each pair are secured to the arms 7 of the Y-shaped plate 8 that is secured to the fan plate 4. The arms 7 are bent out of the plane of the plate 4 and extend substantially parallel to the bracing members 6, as best shown in the left-hand portion of Fig. 3. Portions of the plate 3 are punched out at points substantially half way between the supporting plates 8, leaving 80 wedge-shaped tongues 9 within the openings 10 formed by the punch. The tongues 9 are bent upwardly and their respective end portions 9^a are bent over into a plane 85 substantially parallel to that of the plate 3. Feet 11 bridge the openings 10 and, as best shown in Fig. 4, respectively comprise base portions 12 and a bridge portion 13 that is substantially parallel to the portions 12 and is connected thereto by oppositely disposed 90 inclined portions 14. The base portions 12 are secured to the opposite sides of each opening 10, the intermediate portion 13 being 95 in engagement with the portion 9^a of the plate 3, which partially closes the opening 10, thus aiding in reducing undesirable air currents therethrough. The portions 14 of each foot 11 then lie in planes that are substantially normal to the axes of adjacent 100 bracing members and are respectively pro- 105 110

vided with openings 15 through which the threaded end portions 16 of the bracing members extend, as best shown in the right hand portion of Fig. 3. Nuts 17 and 18 are arranged on opposite sides of the feet 11 to coact with the threaded portions 16 and the portions 14 to place the bracing members 6 in a state of tension. The tension may be adjusted to any desired degree and maintained by reason of the locking action between the nuts 17 and 18. The opening 10 provides easy access to the nut 18 and also provides a means of taking care of the end portion 16 which may extend through the plate 3.

A modification of my invention is shown in Fig. 2 wherein the plate 3 is pressed at properly spaced points to provide portions 19 that project above the surface of the plate 3 and present plane surfaces 20 that are substantially normal to the longitudinal axes of the bracing members 6. The tension of the bracing members may be adjusted in the manner described with reference to Fig. 1.

From the foregoing, it is obvious that, as the tension of the bracing members is transmitted to portions that are substantially normal thereto, a maximum degree of rigidity is secured, and the tendency for the bracing members to tear loose from the plate 3 is substantially eliminated.

While I have shown my invention as applied to a particular type of fan structure, it is not so limited but is susceptible of various modifications within the scope of the appended claims.

I claim as my invention:

1. A centrifugal fan comprising spaced annular plates, a plurality of blades arranged between said plates, bracing members extending obliquely from plate to plate, adjacent pairs of said members being disposed in planes substantially parallel to the axis of said plates, one of said plates being provided with portions integral therewith that are substantially normal to the longitudinal axes of said bracing members through which the said members extend, and means coacting with said portions for placing said bracing means in tension.

2. A centrifugal fan comprising spaced annular plates, a plurality of blades arranged between said plates, bracing members extending obliquely from plate to plate, each of said bracing members being located in a plane that is substantially perpendicular to said plates and defined by chords less than the diameter thereof, and means

for securing said bracing members to one of said plates in planes that are substantially normal to the longitudinal axes of said bracing members.

3. In a centrifugal fan, the combination with spaced annular disks, a plurality of fan blades arranged between said disks, and bracing members extending obliquely between said disks, of a plurality of portions carried by one of said disks and integral therewith to which said bracing members are secured, the said portions respectively comprising plane surfaces, one of which is substantially normal to the coacting bracing member.

4. A centrifugal fan comprising spaced annular plates, a plurality of blades arranged between said plates, and two sets of oppositely disposed bracing members alternately arranged and extending between said plates, each of said members being disposed in a plane that is parallel to and offset with respect to the axis of rotation of said plates.

5. A centrifugal fan comprising two spaced annular plates, a plurality of fan blades arranged between said plates, a plurality of bracing members extending obliquely from plate to plate, adjacent pairs of said members located in planes perpendicular to said plates, and means mounted on each of said plates for securing said bracing members thereto.

6. A centrifugal fan comprising two spaced annular plates, a plurality of fan blades arranged between said plates, a plurality of bracing members mounted in pairs and extending obliquely from plate to plate, the members of each of said pairs being disposed at an angle to each other.

7. A centrifugal fan comprising two spaced annular plates, a plurality of fan blades arranged between said plates, a plurality of bracing members mounted in pairs and extending obliquely from plate to plate, the members of each of said pairs extending in opposite direction.

8. A centrifugal fan comprising two spaced annular plates, a plurality of fan blades arranged between said plates, a plurality of bracing members mounted in pairs and extending obliquely from plate to plate, the members of each of said pairs extending in opposite directions, and means mounted on each of said plates for securing said bracing members thereto.

In testimony whereof I have hereunto subscribed my name this 17th day of Oct., 1916.

ANDREW H. CANDEE.
